(57) **CLAIM**

We claim the ornamental design for a display mount, as shown and described.

DESCRIPTION

FIG. 1 is a first front perspective view of a display mount showing our new design;

FIG. 2 is a rear perspective view thereof;

FIG. 3 is a second front perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a a is a top plan view thereof;

FIG. 9 is a bottom plan view thereof;

FIG. 10 is a rear elevational view of a portion thereof, with the rear bracket and the arm assemblies removed for clarity of illustration;

FIG. 11 is a first front perspective view showing a second position of the display mount of FIG. 1;

FIG. 12 is a rear perspective view of the display mount in FIG. 11;

FIG. 13 is a second front perspective view of the display mount in FIG. 11;

FIG. 14 is a front elevational view of the display mount in FIG. 11;

FIG. 15 is a rear elevational view of the display mount in FIG. 11;

FIG. 16 is a right side elevational view of the display mount in FIG. 11;

FIG. 17 is a left side elevational view of the display mount in FIG. 11;

FIG. 18 is a a is a top plan view of the display mount in FIG. 11;

FIG. 19 is a bottom plan view of the display mount in FIG. 11; and,

FIG. 20 is a a is a rear elevational view of a portion of the display mount in FIG. 11, with the rear bracket and the arm assemblies removed for clarity of illustration.

The broken lines shown are for illustrative purposes only and form no part of the claimed design.
